UNITED STATES PATENT OFFICE.

HOMER E. FROST, OF CLEVELAND, OHIO, ASSIGNOR TO THE ELECTRIC CONTROLLER AND MANUFACTURING COMPANY, OF CLEVELAND, OHIO, A CORPORATION OF OHIO.

ELECTRIC SWITCH.

1,053,489.

Specification of Letters Patent. Patented Feb. 18, 1913.

Application filed January 28, 1911. Serial No. 604,723.

To all whom it may concern:

Be it known that I, HOMER E. FROST, a citizen of the United States, residing at Cleveland, in the county of Cuyahoga and State of Ohio, have invented new and useful Improvements in Electric Switches, of which the following is a specification.

My invention relates to improvements in electric switches, particularly that type which is operated magnetically.

The usual magnetic switch or contactor employs a magnet or solenoid by which a movable arm, carrying one of the contacts of the switch, is moved to make contact with a second contact when the magnet is energized. Upon the deenergization of this magnet the switch falls open either by gravity or by the action of a spring, or a combination of both. The relatively stationary contact with which the moving contact co-operates may be adapted to have a yielding motion when the contacts come together, and if the moving contact strikes the relatively stationary contact with great force it may result in a separation of the contacts due to a rebound caused by the force of impact. This is objectionable because, if the contacts separate after they have once engaged, an arc will be established which will more or less injure the surface of the contacts. Another objection to the form of switch which opens by means of gravity is that upon its striking the limiting open position, the moving arm is liable to rebound, and if this action is great enough the contacts may again come together and cause a second arc in the opening of the switch.

The objects of my invention are—1st—to provide a means for preventing the separation of the contacts due to a rebound caused by the force of impact when the switch closes; 2nd—to prevent the rebound of the moving contact when the switch opens.

To further describe my invention, I refer to the following drawings, in which—

Figure I is a front elevation of a switch embodying my invention; Fig. II, a side elevation, partly in section, of the movable

arm, showing the switch in its closed position; and Fig. III, a side elevation showing the switch in its open position.

In these figures a magnetic frame 1 is mounted upon a suitable insulating support 2. This frame carries a cylindrical projection 3 which forms the core of a magnet on 55 which is mounted the magnetizing winding 4. Pivoted to the frame by means of the pin 5 is the movable arm 6, which is preferably of magnetic material. This arm is forked at its lower portion and passes on 60 either side of the tongue 1^a of the frame 1. This movable arm carries at its upper extremity the contact 7, which when the switch is closed co-operates with the contact 8, which is in turn mounted upon the contact holder 65 9, pivoted at 10 to a frame 11. This frame 11 is suitably mounted upon the insulating support 2. The projection 11^a of the frame 11 is provided to limit the outward travel 70 of the contact 8, the projection 9^a of the contact holder 9 engaging therewith. A compression spring 12 serves to keep the contact 8 in its outermost position when the switch is open, and maintains a pressure between the contacts 7 and 8 when the switch is 75 closed. The positions of the pins 5 and 10 and the point of contact of the contacts 7 and 8 are so related that a wiping action of the contacts is secured as the switch closes, which is desirable for maintaining the surface of the contacts in good condition. 80

Mounted in the arm 6 is a loosely fitting plug or weight 13, of preferably magnetic material, which is provided with the flange 14 to prevent its being drawn through the 85 arm. The stop 15 is attached to the arm and prevents the plug 13 from falling out when the switch is in its open position. The part 16 is a retaining plate fastened to the core 3 for holding the magnetizing winding 90 4 in place. The terminals of the switch are shown at 17 and 18, to which conductors may be connected, the circuit through which is to be closed and opened at the contacts 7 and 8.

This form of switch is adapted to handle 95 very heavy currents through its contacts,

whereas the magnet winding 4 may be energized by means of a very small current and controlled from a distance.

The operation of the switch is as follows:

- 5 Assuming that the switch is in its open position, as shown in Fig. III, as soon as the winding 4 is energized, the plug 13 first is attracted toward the core 3 and closes the gap between its flange 14 and the arm 6.
- 10 The arm and plug are then attracted together toward the core 3 until the contacts 7 and 8 have come together. The air gap between the core 3 and the plug 13 is now smaller and the plug 13 is drawn in until it engages with the core 3, as shown in Fig. II, which action compresses the spring 12. If the energization of the winding 4 is very high this action will take place in a very short time and a considerable blow will be imparted by the contact 7 to the contact 8. When the plug 13 strikes the core 3 it stops but the arm 6 can still progress and it will be brought to rest by further compressing the spring 12, after which 15 the arm 6 is moved by the spring 12 until it comes into engagement with the flange 14 of the plug 13, which is the position shown in Fig. II. If the arm 6 were rigidly attached to the plug 13, the sudden stopping of the contact 7 in the closing of the switch would cause the contact 8 to separate from the contact 7 and thus produce an arc; whereas by my improved construction this separation of the contacts is entirely eliminated and no arc 20 is caused by the closing of the switch, the contacts 7 and 8 being held in contact by the spring 12. To cause the switch to open, the magnet winding 4 is deenergized and the switch falls open by gravity, the motion of 25 the arm being arrested by its striking the surface or stop 1^b on the frame 1. When this position is reached the arm has a tendency to rebound, but the plug or weight 13, continuing its motion until it strikes the stop 15, prevents any appreciable rebound. 30 By a proper proportion of the weight of the plug to that of the arm this rebound will become so small as to be hardly, if at all, noticeable.
- 35 It will thus be seen that the use of the loose plug or weight 13 obviates the two hereinbefore mentioned serious difficulties in the operation of magnetically operated switches of the general type shown.
- 40 I do not limit my invention to the details and their combinations shown and described, but desire protection on all modifications which come within the scope and spirit of the wording of the appended claims.
- 45 I claim—
- 50 1. A pair of contacts one of which is yielding, a movable member carrying one of the contacts, a weight carried by the said member and having a limited free movement.

with respect thereto, means for moving said member and said weight to engage said contacts; and means for stopping the movement of the weight, thereby allowing the said member to continue its movement against the restraining force of the yielding contact. 65

2. A pair of contacts one of which is yielding, a movable member carrying one of the said contacts, the other of said contacts arranged to be engaged by the first contact when the movable member is actuated in one direction, a stop to limit the movement of the said member in the opposite direction, and means carried by the said member to limit its rebound at its opening limit and to prevent the reopening of the contacts at its 70 closing limit.

3. In a magnetically-operated switch, a pair of contacts, a movable member on which one of the contacts is mounted, a loosely fitting weight of magnetic material 85 supported by the said member, means for causing the said contacts to engage, and means for arresting the movement of the said loosely fitting part to allow the said member to continue its motion after the magnetic circuit is closed by the said part.

4. In an electric switch, a movable member carrying an electric contact, a stop to limit the opening movement of the said member, a weight carried by the said member and having a limited movement independently of the said member, and means on the said member for limiting the independent movement of the weight after the movable member has its opening movement arrested by the said stop. 95

5. In a magnetically-operated switch, a pair of contacts, a movable member carrying one of said contacts, a loosely fitting part supported by the said member and located in a magnetic circuit when the switch is closed, means permitting the said part to continue to move a certain distance after the movement of the said member has been arrested, and means to arrest the movement of 100 the said part.

6. A movable contact-carrying member, a contact arranged to be engaged by the contact on the said member when the latter is actuated in one direction, a stop to limit the movement of the said member in the opposite direction, and means carried by the said member to limit its rebound at its opening limit, and to prevent the re-opening of the contacts at its closing limit. 115

7. A movable switch-arm, a weight carried thereby, the arm and the weight having limited independent movement, a contact on the switch-arm, a contact arranged to be engaged by the said movable contact, means to move the switch arm and weight to cause the contacts to engage, means to arrest the movement of the weight, permitting the arm to 125

continue its movement, a stop engageable by the arm at the limit of its opening movement, and a stop on the arm to arrest the independent movement of the weight.

5 8. In a switch, a pair of contacts, a movable member on which one of the contacts is mounted, a weight supported by the movable member and having limited independent movement in the line of movement of

10 the said member, an electro-magnet to actu-

ate the movable member in a direction to cause its contact to engage the other contact, and a stop to arrest the movement of the weight in the said direction.

Signed at Cleveland, Ohio, this 24th day ¹⁵ of January, A. D. 1911.
